CLAIM

The ornamental design for a safety shield for a portable litter, as shown and described.

DESCRIPTION

FIG. 1 is a top, side and rear perspective view of a safety shield for a portable litter showing our new design, the broken lines are for illustrative purposes only and form no part of the claimed design;

FIG. 2 is a top plan view thereof;

FIG. 3 is a side elevational view thereof, the opposite side view being a mirror image of that shown;

FIG. 4 is a rear elevational view thereof;

FIG. 5 is a front elevational view thereof; and

FIG. 6 is a bottom plan view thereof.

Fig. 1
